UNITED STATES PATENT OFFICE.

JOSEPH A. AMELIANOVICH, OF CHICAGO, ILLINOIS.

THERMOSTATICALLY-CONTROLLED SADIRON.

Application filed June 29, 1922. Serial No. 571,787.

To all whom it may concern:

Be it known that I, JOSEPH A. AMELIANOVICH, a citizen of Russia, having declared my intention of becoming a citizen of the United States, and a resident of the city of Chicago, in the county of Cook and State of Illinois, have invented certain new and useful Improvements in a Thermostatically-Controlled Sadiron; and I do hereby declare

5 that the following is a full, clear, and exact description of the same, reference being had, to the accompanying drawings, and to the numerals of reference marked thereon, which form a part of this specification.

10 15 This invention relates to a thermostatically controlled and electrically heated sad iron.

In such a sad iron, a common construction exists in providing an expansible member that will expand and flex away from a contact at a predetermined heat in order to break the electrical circuit that heats the iron. As the ironing heat is usually above the fusing point of most metals, the expansible member would freeze or become partly welded to the contact so that the circuit would not be broken at a predetermined heat, rendering the thermostat inoperative thereby. And in cases where the expansible member did flex away from the contact to some extent, the current would jump the gap and spark. An attempt has been made to remedy this defect by placing a condenser in the circuit, but such condenser did not overcome the freezing together of the contacts, so that no satisfactory thermostatically controlled sad iron is now upon the market.

It is an object of this invention to overcome the above noted defects in providing contacts that will not freeze together and that will eliminate the condenser now commonly used.

It is a further object of this invention to provide a novel sad iron structure in which the thermostat is located substantially centrally of the iron at the point of greatest heat in an improved manner.

With these and other objects in view which will become more apparent in the following description and disclosures in the drawing, this invention comprises the novel

mechanism and combination hereinafter described and more particularly pointed out and defined in the appended claims.

In the accompanying drawings which 55 illustrate a preferred embodiment of this invention and in which similar reference numerals refer to similar features in the different views:

Figure 1 is a top plan view of the sad iron 60 with the handle removed.

Figure 2 is a top plan view of the interior of the sad iron with both the handle and upper housing removed.

Figure 3 is an enlarged elevational view 65 of the thermostat connected in an electrical circuit.

Figure 4 is a section on the line 4-4 of Figure 1.

Figure 5 is a section on the line 5-5 of 70 Figure 1.

Figure 6 is a longitudinal vertical section through the sad iron with the handle in elevation.

In the exemplification of this invention, 75 there is illustrated a sad iron comprising a base member 1 having a central longitudinally extending recess or cavity 2 in which a pair of posts 3 are secured, upon which a pair of flat thin bars 4 and 5 are mounted 80 and insulated from the posts by insulating washers or tubes 6. The ends of the bars 4 and 5 are in contacting relation, but the medial portion of the bar 5, which in the present instance is the lower bar, is bowed 85 away from the bar 4. The bar 5 is made of some resilient material having a large coefficient of linear expansion and may be termed an expansible member.

At the center of the bar 5, and upon the 90 upper side, a contact member 7 having a fusing point higher than the necessary or predetermined temperature required for ironing purposes is secured. The contact member preferably is made of tungsten steel 95 as it is the only satisfactory metal I have been able to discover, the cost of platinum being prohibitive, and I securely anchor the contact member 7 by folding it over the bar 5 to provide a lower portion 8 and extend a 100 screw through the folded contact member and bar 5.

Just above the base 1 the electrical heating means 9, which is usually some high resistance, may be positioned, so that the expandible member 5 is located therebeneath. 5 And over the top of the electrical heating means there is positioned an enclosing member 10 of suitable metal or the like which is secured to the base member 1 by means of screws 11 and nuts 12. The enclosing member 10 is hollowed out upon its under side corresponding to the recess or cavity 2, and a hollow internally screw threaded and headed member 13 extends through an aperture centrally of the hollowed out portion 15 of the enclosing member 10 and is suitably insulated therefrom and clamped thereto by a nut 14. The hollow member 13 is in axial alignment with the tungsten contact 7 and is adapted for adjustably receiving a contact screw 15 preferably having a lower contact portion of higher fusibility than the ironing temperature. The contact screw 15 may be made of tungsten steel or the like, or the lower contact portion only may be made of tungsten. The screw 15 is adjustably held in the hollow member 13 and extends through an aperture in the plate 4 and into contact with the contact member 7.

The enclosing member 10 is provided with 30 a plurality of insulated posts or terminals for the ingress and egress of the electrical current to the heating medium. The current may enter through the terminal 16 which is electrically connected to the expandible member 5 by a conductor 17 (Figure 2). The current will flow from the expandible member 5 through the screw 15 and through an electrical conductor 18 connected to the screw at one end and connected at 40 its other end to the terminal 19 which in turn is suitably connected as by a conductor 20 with the heating resistance 9. After the current traverses the heating means or resistance 9 it emerges through the terminal post 21 which is connected to the resistance by a conductor 22.

The top of the sad iron is formed by a cover 23 which is provided with downwardly extending flanges which fit in rabbets formed 50 in the base 1, the rear end of the cover being provided with a hollow extension for receiving the electrical conductors as usual. The cover is so constructed that its upper part will be in spaced relation to the resistance enclosing member 1. The upper portions of the screws 11 are reduced in diameter and extend through apertures in the cover 23 for receiving the handle 24; nuts 25 being threaded upon the upper ends of said screws 60 11 for securing the cover and handle to the base 1.

The upper end of the screw 15 is likewise reduced and extends through an aperture in the cover 23, the upper end of said screw 65 15 having a pointer 26 rigidly attached thereto

which moves over a circular scale 27 which indicates the desired temperature. By rotating the pointer 27 to the point of the scale denoting the desired temperature, the screw 15 will be slightly raised or lowered 70 for varying the tension of the expandible bar 5 so that the expansion thereof will break the contact at the predetermined temperature.

In Figure 3 is diagrammatically illustrated the thermostat in an electric circuit, the current entering through the wire "a" passing through the bar 5, contact screw 15, the heating resistance, and emerging through the conductor "b". It will be evident that 80 when the bar 5 expands it will flex away from the contact screw 15.

It is characteristic of this invention that the thermostatic contact members or points consist of metal having a higher fusion point than the necessary or usual ironing temperature, so that the contact members will not become frozen or partially fused together during the use of the sad iron. It is further a characteristic of this invention that 85 sparking between the thermostatic contact members is eliminated by the character of the metal of which the contact members are made and no condenser is necessary in the circuit. It should also be noted that the 90 thermostat is located centrally of the iron beneath the heating resistance medium so that the true temperature is controlled.

I am aware that numerous details of construction may be varied through a wide 100 range without departing from the principles of this invention and I therefore do not purpose limiting the patent granted otherwise than necessitated by the prior art.

I claim as my invention:

1. In a sad iron, a heating resistance, means for passing an electric current therethrough including a contact member of tungsten steel, and an expandible bar having a contact member of tungsten steel normally 110 engaging said first contact member, said expandible member being actuated by heat emanating from said means to separate said contact members.

2. In a sad iron, a heating element, means for passing an electric current therethrough, including an adjustable contact member embodying a temperature indicator and having a contact terminal of tungsten steel, and an expandible member having a contact portion of tungsten steel normally engaging the contact terminal of said first member.

3. In a sad iron, an ironing base having a substantially central and longitudinally extending recess, a pair of spaced posts in 125 said recess, a resilient and expandible strip having a contact member of tungsten steel supported on said posts, an enclosing member superposed on said base, a rotatable screw supported by said enclosing member 130

and having a contact end of tungsten steel normally engaging said contact member, a heating means associated with said base, and electrical connections for passing a current through said means, expansible member and screw.

In testimony whereof I have hereunto

subscribed my name in the presence of two subscribing witnesses.

JOSEPH A. AMELIANOVICH.
